UNITED STATES PATENT OFFICE.

JOHN ROWLAND BROWN, OF MANSFIELD, OHIO, ASSIGNOR TO THE OHIO BRASS COMPANY, OF MANSFIELD, OHIO, A CORPORATION OF NEW JERSEY.

BOND.

1,189,235.

Specification of Letters Patent.

Patented July 4, 1916.

Application filed April 6, 1914. Serial No. 829,730.

To all whom it may concern:

Be it known that I, JOHN ROWLAND BROWN, a citizen of the United States, residing at Mansfield, in the county of Rich-
5 land and State of Ohio, have invented cer-
tain new and useful Improvements in Bonds, of which the following is a speci-
fication.

My invention relates to improvements in
10 the terminals of bonds used for making
electrical connections between the rails of a
railroad track.

One of the objects of my invention is to
provide an improved device of this charac-
15 ter which will be simple, durable and re-
liable in construction, effective and efficient
in operation and inexpensive to manufac-
ture.

Other objects of my invention will ap-
20 pear hereinafter.

Referring to the accompanying drawings,
Figure 1 is a view in elevation of a par-
tially completed bond terminal embodying
my invention. Fig. 2 is a sectional view of
25 the completely formed terminal. Fig. 3 is
a top plan view of the structure shown in
Fig. 2. Fig. 4 is a sectional view on line
4-4 of Fig. 1. Fig. 5 is a view of a portion
30 of the cable used for bonds of this charac-
ter and showing one of my protecting
sleeves which is positioned thereon prior to
the formation of the completed bond termi-
nal. Fig. 6 is a top plan view similar to
35 Fig. 3 of a modified construction wherein
two cable strands are used instead of one.
Fig. 7 is a similar view of another modi-
fication. Figs. 8, 9 and 10 are end views of
modified forms of protector sleeves. Fig.
40 11 is a sectional view of another modifica-
tion adapted for ribbon strand cables, and
Fig. 12 is a side elevation of the completed
structure shown in Fig. 11.

My invention is more particularly directed
45 to bonds of the type wherein a solid
metal terminal is welded to a flexible metal
conductor. In this type of bond the termi-
nal is formed of a solid piece of metal, pref-
erably forged, and the flexible conductor or
50 cable is composed of a plurality of wires,
strands or ribbons twisted or assembled to-
gether, as the case may be, and intimately
secured to the solid terminal by welding
operations. In manufacturing these bonds
the terminal is provided with a suitable

socketed or bored out portion into which the 55
end of the flexible or stranded conductor is
inserted. After being assembled in this
manner the terminal and flexible cable are
subjected to heating and compressing oper-
ations to intimately weld or join the two 60
together. The effect of this compressing
and heating operation is to cause the flexi-
ble cable to merge into the solid terminal;
that is to say, the strands of the flexible
conductor gradually lose their identity as 65
individual strands and become incorporated
into the solid mass of metal in the terminal.
The strands of the conductor adjacent the
junction thereof with the solid terminal,
in spite of all precaution, necessarily be- 70
come damaged and disintegrated to a more
or less degree because of the compression
and burning or scorching to which they are
subjected in the welding operation. The
result is that the strands adjacent the 75
junction, and particularly the outer strands of
the cable in this more or less weakened con-
dition eventually give way and break when
the bond is subjected to the various strains
and bending action in use. The breaking 80
of these strands, of course, reduces the cur-
rent-carrying capacity of the bond and ren-
ders it objectionable for obvious reasons. I
propose, therefore, to provide a protector
sleeve or guard around the strands of the 85
cable adjacent the junction of the cable and
terminal for the purpose of protecting the
strands at this point during the manufac-
turing process. This protecting sleeve or
member is interposed between the cable and 90
the metal of the terminal in such manner
that when the terminal and cable are sub-
jected to the welding operation a portion of
this sleeve is likewise treated and becomes
intimately incorporated into the solid 95
mass of the terminal itself. Another por-
tion of the sleeve, however, extends along
the cable and projects beyond the metal of
the terminal itself. It takes the brunt of
the welding operation so that at the point 100
where the cable merges or leaves the termi-
nal the strands thereof remain whole and
uninjured and thereby better able to with-
stand service without damage. The protector
is preferably of comparatively thin material 105
and yields to some extent when the cable is
bent adjacent the juncture with the termi-
nal. The protector, therefore, operates to

distribute the bending action over a greater length of cable and therefore prevents sharp bends.

My invention may be carried out in various ways without departing from the scope and spirit thereof, and in the drawings I have illustrated several forms of bonds which embody my invention.

In Fig. 1 it will be seen that the terminal A is of solid metal and is provided with a bore or socket C in one end into which the end of the flexible stranded cable D is inserted prior to the welding operation. Surrounding the end portion of the cable which is inserted into this socket is a guard or protector sleeve E. This sleeve is made of any suitable material for the purpose and is preferably comparatively thin, as shown more clearly in Figs. 4 and 5. It is given the form of an open-ended tube and is temporarily held in place on the cable in any desired manner, such for instance, as by bending or crimping it as at E². The parts are so proportioned that a portion of this sleeve 25 extends along the cable or conductor D and projects beyond the end C¹ of the metal of the terminal. The terminal cable and sleeve are now subjected to heating and compressing operations, the result of which intimately incorporates the inner portion of the sleeve and the end portion of the cable D into the mass of metal of the solid terminal, the sleeve and strands of the cable practically gradually losing their identity in the 30 mass of metal of the terminal, this being clearly indicated in Fig. 2. The portion of the sleeve which projects beyond the end C¹ of the metal guards the strands of the cable against burning or compression during the 35 welding operation, and in consequence the cable merges from the terminal in an uninjured condition.

Fig. 3 illustrates a single strand cable in a completed condition. The terminal itself may be of any shape or form desired. In the drawings I have shown the terminal A as being provided with a cylindrical stud or shank B by which the terminal may be secured in the bond-holes in the rails.

In Figs. 6 and 7 I have illustrated a duplex type of bond; that is, a bond wherein two flexible cables instead of one are used. In Fig. 6 the terminal is divided at one end into two separated tubular portions each provided with a socket for the reception of a single cable D, while in Fig. 7 the two cables D enter together into a common socket or bore in the terminal, but the principle involved is the same as described above. In Fig. 6 I employ a single sleeve E for each cable similar to the one described in connection with Fig. 1. In Fig. 7, however, I have provided a sleeve common to both of the cables. The sleeves for the type of bond shown in Fig. 7 may be formed in various

ways, such for instance as shown in Figs. 8, 9 and 10, which are end views of modifications of double sleeves for the Fig. 7 form of bond.

Figs. 11 and 12 are of the type in which the cable or flexible conductor is composed of a plurality of flat ribbon strands instead of wire strands, as above described. The terminal A is provided with a suitable groove or opening into which the end portions of the ribbon conductors are placed. This construction also employs a sleeve E for each cable, the same as described above, but the sleeve will, of course, necessarily be rectangular in form rather than circular. After the ribbon strands and sleeves have been placed in position the terminal and cables are subjected to the welding operations in the same manner as the terminals above described.

I claim:

1. The combination of a terminal member and a stranded conductor consolidated together in varying degrees of intimacy, and an auxiliary protector sleeve surrounding the stranded member at the point where it emerges from the terminal member.

2. The combination of a solid metallic terminal member and a conductor member composed of a plurality of metallic strands, consolidated together in varying degrees of intimacy, and an auxiliary sleeve surrounding the strands of the conductor at the point where said conductor emerges from the terminal.

3. A bond of the class described comprising a socketed terminal, a flexible stranded conductor positioned within the socket of said terminal, and a separate protector sleeve surrounding said stranded conductor and interposed between the metal of the terminal and the conductor.

4. A bond of the class described comprising a solid metal terminal, a flexible stranded conductor extending into said terminal and intimately welded therewith, and a separate protector sleeve surrounding the stranded conductor within the terminal and intimately welded with said terminal and conductor.

5. A bond of the class described comprising a solid metal terminal, a flexible stranded conductor extending into said terminal and intimately welded therewith, and a protector sleeve surrounding the stranded conductor within the terminal and intimately welded with said terminal and conductor, a portion of said sleeve projecting along the conductor and beyond the metal of the terminal.

6. A bond of the class described comprising a solid metal terminal having a socket, a flexible conductor comprising a plurality of strands inserted into said socket and intimately welded into the mass of said termi-

nal, and a protector sleeve surrounding the strands of the conductor and interposed between the metal of the terminal and the strands of the conductor and intimately 5 welded with said terminal and said conductor, said protector sleeve projecting beyond the metal of the terminal.

7. A bond comprising a socketed terminal, a flexible stranded conductor consolidated 10 within the terminal with it, and a separate protector sleeve surrounding the conductor and extending partially within and partially without the socket of the terminal.

8. A bond comprising a socketed terminal, 15 a flexible stranded conductor extending

within the socket and welded thereto, and a separate protector sleeve surrounding the conductor extending partially within the socket and welded therein to the terminal, and extending outwardly beyond the metal 20 of the terminal.

In testimony whereof I have signed my name to this specification, in the presence of two subscribing witnesses, on this 31st day of March A. D. 1914.

JOHN ROWLAND BROWN.
